ANCHOR FOR GROUND SUPPORTS

John B. Hyde, Great Neck, N. Y.

Application September 5, 1942, Serial No. 457,469

1 Claim. (Cl. 189—29)

This invention relates to anchors for ground supports.

This application is a continuation in part of my copending application Serial No. 232,329, filed September 29, 1938, entitled Animal tether, now Patent No. 2,295,581, issued September 15, 1942.

Preferred embodiments of my present invention are specifically directed to anchors for various purposes, such as machine gun assemblies and other war devices and assemblies, and also for flag poles, fence posts, Christmas trees, poles for tennis, badminton, volley ball nets and for clothes lines and the like, for street, golf, traffic markers and the like, and other like objects requiring ground anchorage.

An object of the invention is to provide efficient anchorage means affording secure footing in the ground or like for machine gun assemblies and like equipment and other devices.

An object of the invention is to provide anchoring means which may be speedily and securely positioned in the ground or the like.

An object of the invention is to provide such anchoring means which is simple in assembly, light in weight, adapted to be positioned in the ground by ordinary tools, and also possessing the attribute of being readily and quickly removable.

Further features and objects of the invention will be more fully understood from the following detail description and the accompanying drawing, in which

Fig. 1 is a perspective view, partly in section, of a two section embodiment of the invention, illustrated in mutually joined position;

Fig. 2 is a perspective view of another embodiment of the invention, partly broken away to illustrate their mutual joining arrangement.

Referring to the drawing and particularly to Fig. 1, the two sections 20, 20 of the illustrated embodiment are of suitable material molded or otherwise shaped into a general semi-circular or other suitable arcuate configuration, and having a reverse bend at substantially its central portion 21, so that when the two sections 20, 20 are placed in opposed position, and driven edgewise in the ground, their reverse bends 21, 21, face one another to form a collar. Such collar 21, 21, is adapted to receive a stake or post 22, of an animal tether or to receive the post of a machine gun assembly or the like.

The anchor sections are preferably fabricated of metal, such as iron, steel or the like, and are of suitable thickness to insure sufficient strength and yet afford ready edgewise insertion into the ground, as by the use of a mallet or other simple impact tool. To facilitate entry and position in the ground, the edges of the sections may be tapered.

The anchor sections are assembled in the ground in opposed position and in mutually engaging relation by means of opposingly related and mutually engaging notches 28, 29. It will be observed that each section has its notch 28 extending from one edge at one side of its central bend and its other notch 29 extending from its opposite edge at the opposite side of its central bend.

10 In Fig. 2 is illustrated an assembly comprising two substantially S-shaped sections 20^a and 20^b provided at their central portions with mating, opposingly extending bends 21 of arcuate substantially hemi-circular shape forming a socket 15 for a post, pile, or the like. The assembly is of substantially propeller configuration and the S-shaped members 20^a and 20^b are crossed at a single point adjacent the socket formed by the bends 21. The S-shaped members are provided 20 at their points of crossing with interfitting grooves or recesses 28 and 29 which interlock the crossed S-shaped members adjacent said central socket.

At a point adjacent said socket and diametrically opposite said point of crossing, the members are arranged in abutting engagement and the pair of curved arms of each of the S-shaped sections are diagonally disposed with relation to each other and form with the arms of the other section said propeller formation.

As appears from the foregoing, my invention in its variant forms provides an anchorage particularly applicable to be readily and speedily driven into the ground or equivalent, composed of parts 35 or sections of substantially rigid strap material such as metal, each part or section being of arcuate formation to provide blade-like arms, the parts or sections being arranged to be mutually coordinated preferably by opposingly related and 40 mutually engaging notches formed in the respective arms, to form a rigid anchorage.

I claim:

An anchoring device arranged to be driven into the ground or the like comprising two substantially S-shaped sections provided at their central portions with mating, opposingly extending bends forming a central socket, said members being crossed at a single point adjacent said central socket and arranged in side by side abutting relation adjacent the socket at a point diametrically opposite said point of crossing, each of said sections forming a pair of curved arms arranged diagonally with relation to each other and the arms of the two sections providing a propeller-like formation.

JOHN B. HYDE.
